UNITED STATES PATENT OFFICE.

PATRICK JOSEPH ENRIGHT, OF LOWELL, MASSACHUSETTS.

RAZOR-BLADE HOLDER.

No. 884,805.

Specification of Letters Patent. Patented April 14, 1908.

Application filed July 31, 1907. Serial No. 386,377.

To all whom it may concern:

Be it known that I, PATRICK JOSEPH ENRIGHT, a citizen of the United States, residing at Lowell, in the county of Middlesex, State 5 of Massachusetts, have invented certain new and useful Improvements in Razor-Blade Holders, of which the following is a description, reference being had to the accompanying drawing and to the letters and figures of reference marked thereon.

This invention relates to holders for the blades of safety razors, and has for its principal object to provide a holder of very simple construction, which will firmly clamp and 15 retain thin flexible blades of the Gillette type, during the stropping or honing operations.

A further object of the invention is to provide a novel construction of holding clamp in which the clamping members are of such 20 nature as to provide an interlock, without any projection which would engage with and tend to injure the strap or hone, and which at the same time will effectually clamp and hold the blade from accidental displacement.

With these and other objects in view, as will more fully hereinafter appear, the invention consists in certain novel features of construction and arrangement of parts, herein- 25 after fully described, illustrated in the accompanying drawings, and particularly pointed out in the appended claims, it being understood that various changes in the form, proportions, size and minor details of the structure may be made without departing from 30 the spirit or sacrificing any of the advantages of the invention.

In the accompanying drawings: Figure 1 is a perspective view of a razor holder constructed in accordance with the invention; 40 Fig. 2 is a transverse sectional view of the same; Fig. 3 is a side elevation, showing the clamp partly open; and Fig. 4 is a detail view of the locking device.

Similar numerals of reference are employed 45 to indicate corresponding parts throughout the several figures of the drawings.

The holder comprises a clamping plate 10, that is preferably formed of thin sheet metal, and is concavo-convex in cross section, pre- 50 senting two relatively sharp gripping edges for contact with one face of the blade x . The rear end of the arm 10 is formed integral with a tapered ferrule or sleeve 11 that fits on a carrying and operating handle 12, that 55 may be formed of any desired material. The extreme outer end of the arm is flattened,

and is provided with a centrally disposed opening for the passage of a pivot pin 15.

Secured to the concave inner face of the arm 10 are two or more studs 16, that are 60 properly spaced to engage in the end openings formed in blades of the Gillette type, and the upper ends of these studs project beyond the plane of the edges of the arm 10 a distance about equal to the thickness of 65 the blade.

The second or movable clamping arm 17 is formed of die struck sheet metal, and it is, also, concavo-convex in cross section to present a pair of clamping edges opposing those 70 of the arm 10. The outer end of the arm 17 is provided with an opening for the passage of the pin 15, and the arms are opened and closed by a swinging movement in a direction parallel with the plane of their clamping sur- 75 faces.

The arm 17 is sprung in the direction of its length, so as to present a convex surface to the blade when the arm is in open position, as more clearly shown in Fig. 3, and in order 80 to move the arm to closed position, it becomes essential to press down on its free or inner end, and then swing the arm on the pivot 15. In this manner, the convex face of the arm is forced down gradually on to the 85 surface of the razor blade, so that the latter is clamped and held positively throughout its entire length.

In order to hold the inner end of the arm 17, said arm is provided with a projecting 90 tongue 18, the end of which is disposed obliquely to the transverse plane of the arm, and this tongue is arranged to fit within a recess that is formed under shoulders 19 cut in the end of the ferrule or sleeve 11. In order 95 to make this lock more positive and increase the strength of the free end of the arm, the tongue 18 is preferably formed of a separate block of metal that is soldered or otherwise secured within the end of the arm proper. 100 The extreme end of the shoulder 18 is obliquely disposed as before described, and the end wall of the recess is correspondingly inclined, so as to form a stop with which the end of the tongue engages, in order to limit 105 swinging movement of the arm 17.

It is found in practice, that the elasticity of the arm 17 will firmly hold the same from movement from under the shoulder 19, and as a matter of fact, there is little or no lateral 110 strain imposed on the arm during the strapping or honing operation, this strain being

imposed on the studs 16 that are carried by the rigid arm 10.

The outer faces of the arms being convex, will freely slide over the strap or hone, and they stand out a sufficient distance to hold the blade at the proper angle to the surface. The locking or connecting means between the arms offer no projections to engage with the strap or hone, so that danger of injury from this cause is avoided.

Having thus described my invention, what I claim as new and desire to secure by Letters Patent, is:—

1. A razor holder, comprising a pair of arms, concavo-convex in cross section to present a pair of parallel clamping edges, means for pivoting the outer ends of the arms together to permit separation and closure of the arms in a direction parallel with the plane of their clamping surfaces, and means for interlocking the free ends of the arms.

2. A razor holder, comprising a pair of arms pivoted together at their outer ends, one of said arms having an integral handle member and the other being initially curved or sprung to present a concavo-convex surface to the blade to form parallel clamping edges, a tongue carried by the free end of the

movable arm, and a locking shoulder carried by the handle member and with which said tongue engages.

3. In a razor holder, a clamping arm formed of sheet metal, and concavo-convex in cross section to present a pair of parallel clamping edges, a sleeve or ferrule formed integral with said arm and provided with an inclined tongue-receiving slot and a shoulder, the outer end of said arm being flattened, a second movable clamping arm also concavo-convex in cross section, and having a flattened outer end that is pivoted to the outer end of the stationary arm, the movable arm being sprung or curved in the direction of its length to present a convex surface to the blade, a tongue projecting from the free end of the movable arm, the end of the tongue being inclined to correspond to the inclination of the wall of the slot, and a pair of razor blade engaging studs projecting from the stationary arm.

In testimony whereof I affix my signature in presence of two witnesses.

P. JOSEPH ENRIGHT.
